SUPPORT AND GAUGE FOR CURTAIN RODS

Natale Terzo, New York, N. Y., assignor to John Terzo, New York, N. Y.

Application July 8, 1937, Serial No. 152,499

5 Claims. (Cl. 156—22)

This invention relates to new and useful improvements in a support and gauge for curtain rods.

The invention has for an object the construction of an article as mentioned which is adapted to support a curtain rod at various pre-determined elevations.

Still further the invention proposes to characterize the support and gauge for curtain rods by the provision of two identical brackets adapted to be attached to opposite sides of a window frame and adapted to support vertical rods on the upper ends of which the curtain rod is supported.

15 It is proposed to characterize each of the brackets by a base plate and a clamp plate hingedly connected thereto and formed with a vertical slot having a plurality of branches to receive a projection from the support rod and so support the same in various desired positions.

Still further the invention also proposes to hingeably connect the clamp plate and the base plate bracket so that they may be readily separated when desired.

20 Another one of the objects of this invention resides in a novel arrangement of normally holding the clamp plate and the base plate together.

For further comprehension of the invention, and of the objects and advantages thereof, reference will be had to the following description and accompanying drawing, and to the appended claims in which the various novel features of the invention are more particularly set forth.

25 In the accompanying drawing forming a material part of this disclosure:—

Fig. 1 is a front elevational view of a window provided with a curtain rod supported according to this invention.

30 Fig. 2 is a plan view of the curtain rod and support shown in Fig. 1.

Fig. 3 is a perspective view of a curtain rod adapted to be supported according to this invention.

35 Fig. 4 is a perspective view of one of the support rods.

Fig. 5 is a perspective view of one of the support brackets.

Fig. 6 is a horizontal sectional view taken on the line 6—6 of Fig. 5.

Fig. 7 is a perspective view of another curtain rod constructed according to this invention.

A curtain rod 10 is adapted to be supported above a window 11 and is supported by side support rods 12. These side support rods extend

downwards to support brackets 13 which are attached to the window frame. An arrangement is provided to support the support rods 12 at various elevated positions upon the brackets 13 so as to correspondingly support the curtain rod 10. It is thus possible to adjust the position of a supported curtain. Furthermore, it is possible to conveniently remove the curtain when desired without the necessity of climbing up to where it is hung.

The curtain rod 10 comprises a pair of adjacent sections 10^a and 10^b which telescopically engage each other. The free ends of these sections are bent rearwards. Tubular elements 10^c are mounted upon the bent free ends and are adapted to engage the top ends 12^a of the support rods 12. Each support rod is provided with a collar 12^b immediately below the top portion against which the portions 10^c of the curtain rod may rest.

The curtain rod 10 illustrated particularly in Figs. 1, 2 and 3 is of flat construction made from a strip of material having its edge portions bent inwards. Fig. 7 illustrates another type of curtain rod 10' which is formed from tubular portions. The purpose of this illustration is to bring out that the particular design of the curtain rod is immaterial, provided it is adapted to be supported on the upper ends of the support rods 12. The curtain rod 10' comprises a pair of telescopic tube portions 10^{aa} and 10^{bb}, the free ends of which are bent rearwards. L-shaped tubular extensions 10^{cc} extend downwards and adapted to engage upon the portions 12^a of the support rods 12 and rest upon the collars 12^b thereof.

Each bracket 13 is essentially formed from a base plate 13^a and a clamp plate 13^b hingedly and slightly slidably mounted on one edge of said base plate. Fastening elements 15 are provided for attaching the base plate 13^a on a window frame or the like and these fastening elements have heads 15^a engaging into bayonet slots 16 formed in the clamp plate 13^b for holding the clamp plate against motion when it is in its lowered position.

The hinged connection of the clamp plate and the base plate is formed as follows: From the base plate 13 there projects along one of the edges thereof tubular portions 17 preferably formed by coiling edge portions thereof. Spaced a small distance below these tubular portions there are other tubular portions 18 which project from the adjacent edge of the clamp plate 13^b. Hinge pintles 19 engage through adjacent tubular por-

tions 17 and 18 respectively. Interposed between each pair of portions 17 and 18 there is an expansion spring 20 normally holding the tubular portions 17 and 18 spaced apart but permits them to be forced together when the clamp plate 13^b is moved upwards. When the clamp plate is so moved the bayonet slots 16 will assume their disengaged positions. Each of the bayonet slots has a restricted upper end and an enlarged lower end. When the enlarged lower end is in line with the head 15^a of its fastening element the fastening element is inoperative as far as the clamp plate is concerned.

The clamp plate 13^b is formed with a vertically extending projecting portion 13^d adapted to receive the lower end of the support rod 12. The support rod 12 at its lower end portion is formed with a laterally projecting handle portion 12^c. This handle portion 12^c is adapted to extend 20 through a longitudinally extending slot 21 in the clamp plate 13^b. This slot 21 is formed with a plurality of horizontal branches 21^a. The arrangement is such that the projecting element 12^c may be engaged into any one of the branches 25 21^a for supporting the support rod 12 in selected positions.

The operation of the device is as follows:—

When in the position as illustrated in Fig. 1 it is capable of supporting a curtain. When desired 30 the elements 12^c of each of the support rods 12 may be slightly turned, since there is no holding means preventing turning, until the projecting elements 12^c are in line with the slots 21. Then the rods 12 may be lowered to completely lower 35 the curtain rod 10. The curtain rod may easily be reached and a curtain mounted or removed thereon or adjusted as it is desired.

To replace the curtain it is merely necessary that the projecting elements 12^c be moved upwards 40 along the slots 21 to the proper elevations and then the rods 12 turned laterally either inwards or outwards to engage them into certain of the branches 21^a and then they are automatically maintained in this position. In other words the 45 rods 12 are then supported by the projections 12^c resting on the bottom edges of the branch slots 21^a.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:—

1. In a support and gauge for curtain rods, a base plate, a clamp plate hingedly and slightly 60 slidably mounted on one edge of said base plate, fastening elements for attaching said base plate on a window frame or the like and having heads engaging bayonet slots in said clamp plate for holding said clamp plate against hinging in its lowered position, a curtain rod support engaging in a groove formed between said plates, and an element on said rod engaging one branch of a slot with a plurality of branches formed in said clamp plate for supporting said rod in an elevated 65 position.

2. In a support and gauge for curtain rods, a

base plate, a clamp plate hingedly and slightly slidably mounted on one edge of said base plate, fastening elements for attaching said base plate on a window frame or the like and having heads engaging bayonet slots in said clamp plate for holding said clamp plate against hinging in its lowered position, a curtain rod support engaging in a groove formed between said plates, and an element on said rod engaging one branch of a slot with a plurality of branches formed in said clamp plate for supporting said rod in an elevated position, said hinged and slidale connection comprising tubular portions turned in from the edges of the base plate and clamp plate and superimposed and slightly spaced from each other, pintles engaging through said tubular portions, and expansion springs coaxial upon said pintles and disposed between said tubular portions.

3. In a support and gauge for curtain rods, a base plate, a clamp plate hingedly and slightly 20 slidably mounted on one edge of said base plate, fastening elements for attaching said base plate on a window frame or the like and having heads engaging bayonet slots in said clamp plate for holding said clamp plate against hinging in its 25 lowered position, a curtain rod support engaging in a groove formed between said plates, and an element on said rod engaging one branch of a slot with a plurality of branches formed in said clamp plate for supporting said rod in an elevated 30 position, said hinged and slidale connection comprising tubular portions turned in from the edges of the base plate and clamp plate and superimposed and slightly spaced from each other, pintles engaging through said tubular portions, and expansion springs coaxial upon said 35 pintles and disposed between said tubular portions, said fastening elements comprising headed screws or the like.

4. In a support and gauge for curtain rods, a base plate, a clamp plate hingedly and slightly 40 slidably mounted on one edge of said base plate, fastening elements for attaching said base plate on a window frame or the like and having heads engaging bayonet slots in said clamp plate for holding said clamp plate against hinging in its lowered position, a curtain rod support engaging in a groove formed between said plates, and an element on said rod engaging one branch of a slot with a plurality of branches formed in said 45 clamp plate for supporting said rod in an elevated position, said groove comprising the inner side of a projecting portion formed in the clamp plate.

5. In a support and gauge for curtain rods, a base plate, a clamp plate hingedly and slightly 55 slidably mounted on one edge of said base plate, fastening elements for attaching said base plate on a window frame or the like and having heads engaging bayonet slots in said clamp plate for holding said clamp plate against hinging in its lowered position, a curtain rod support engaging in a groove formed between said plates, and an element on said rod engaging one branch of a slot with a plurality of branches formed in said 60 clamp plate for supporting said rod in an elevated position, said clamp plate being formed with a main slot through which said element may pass, and said branch slots being formed in the sides of said main slot.

NATALE TERZO.
